FRANK B. MORRISON, OF TOLEDO, OHIO, ASSIGNOR, BY MESNE ASSIGNMENTS, TO THE MORRISON AUTOMATIC SAFETY VALVE COMPANY, OF TOLEDO, OHIO, A CORPORATION OF ARIZONA TERRITORY.

COMBINED ANGLE-COCK AND SAFETY-VALVE.

SPECIFICATION forming part of Letters Patent No. 772,953, dated October 25, 1904.

Application filed February 26, 1903. Serial No. 145,117. (No model.)

To all whom it may concern:

Be it known that I, FRANK B. MORRISON, a citizen of the United States, residing at Toledo, in the county of Lucas and State of Ohio, have invented certain new and useful Improvements in a Combined Angle-Cock and Safety-Valve; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in angle-cocks for fluid-pressure brake systems, and particularly to improvements on the invention described and claimed in my application for United States Letters Patent filed August 15, 1902, being Serial No. 119,770.

The objects of my invention, in addition to preventing the sudden application of the brakes when an air-hose bursts or the hose-couplings become disconnected, as set forth in my said application, are, first, to provide an angle-cock whereby a brakeman can control the brakes on a detached car or cars by manipulating the handle of the angle-cock in the same manner as an engineer controls the brakes 30 on his train by means of the engineer's valve; secondly, to so construct the safety-valve in the angle-cock that it will be absolutely under the control of the engineer at all times when the angle-cock is open and may be released from closed position by the proper manipulation of the engineer's valve, and, thirdly, to provide improved means for preventing the turning of the angle-cock plug by unauthorized persons.

40 While the essential features of my invention are necessarily susceptible of modification, the preferred embodiment thereof is illustrated in the accompanying drawings, in which—

45 Figure 1 is a vertical central sectional view of my invention, showing the handle and valve-plug of the angle-cock thrown into full-open position. Fig. 2 is a similar view thereof,

showing the valve shot and the train-line closed. Fig. 3 is a cross-sectional view taken on the dotted line $x-x$ in Fig. 2, showing the valve-plug of the angle-cock turned into closed position. Fig. 4 is a vertical sectional view of the valve portion of my angle-cock, showing my improved means for locking the angle-cock plug when in open position to prevent it from being turned. Fig. 5 is a similar view showing the valve shot and the lock in released position, and Fig. 6 is a cross-sectional view taken on the dotted line $x-x$ in Fig. 2 and showing the valve-plug turned to what is termed "on-lap" position.

Like letters and figures of reference indicate the same parts in all the figures of the drawings.

Referring to the drawings, A represents the casing of an ordinary angle-cock; B, a hollow valve-plug; C, the handle for turning the same, and D the sleeve or bushing of the angle-cock, which forms a seat for the valve-plug B. The valve-plug and bushing are provided with the usual openings to establish a free passage-way through the train-line when the valve-plug is in open position.

An air-chamber 1' of suitable size to house the valve-casing and piston is formed by screwing the cylindrical casing 1 at 3 into the opening in the bottom of the angle-cock, usually closed by the screw-cap 2, and the bottom of this casing 1 in turn receives the said screw-cap 2. The lower portion of the hollow valve-plug B extends down loosely into the chamber 1' and forms the piston-chamber 4 therein. The bottom of said plug B rests upon the perforated disk 5, which receives the thrust of the coiled spring 6, thus holding said valve-plug tightly to its seat within the bushing D. The disk 5 affords a seat or support for the piston operating within the chamber 4, and perforations 5' are provided in said disk to establish a free circulation of air between the chambers 1' and 4. A piston 7 is movably mounted in the chamber 4 and carries the valve-stem 8, the said stem being tapered to adapt it to seat in the upper tapered hollow portion of the valve-plug B when a pressure

is exerted upon the under side of said piston, thus closing the passage in the train-line. A seat 9, of leather or other suitable material, is secured within the valve-plug B to form a cushion for the valve-stem 8 when shot.

In order to reduce the size of my angle-cock and economize in space and material, I make the piston 7 and stem 8 hollow, as shown in the drawings, thus forming a chamber 7' therein and reducing the space heretofore required in valves of this class for storing the air with which to force the stem 8 to its seat when a break occurs in the train-line.

I will now proceed to describe the means of communication provided between the train-line and the several chambers of my valve.

The grooves or passage-ways 10 and 11 are formed in the side of the valve-plug B at substantially a right angle to each other with respect to the center of the plug and form the ingress and egress passage-ways, respectively, for the fluid between the train-line and the chamber 1' of my valve, the said chamber 1' in turn communicating with the chambers 4 and 7' through the perforated disk 5. These passage-ways are so arranged in the plug B with respect to the train-line that when the angle-cock is open, as shown in Figs. 1 and 2, the ingress-passage 10 will communicate with the side A' of the angle-cock and the passage 11 will be closed, and when the angle-cock is closed, as shown in Fig. 3, the egress-passage 11 will communicate with the side A" of the angle-cock and the passage 10 will be closed. A third passage-way or port 12, the purpose of which will be hereinafter more fully set forth, is provided through one side of the plug B to afford communication between the side A" of the angle-cock and that portion of the piston-chamber 4 above the piston 7, the sleeve or bushing D being either cut away or grooved on that side, as shown at 13.

My improved lock consists of the lever or inverted-T-shaped member 14, which is fulcrumed to the tenon 15, suitably secured to the inner side of the cap 2', Figs. 4 and 5. The long arm of the lever 14 extends up through an elongated slot 5" in the disk 5" into the interior of the chambers 4 and 7'. The end of the short arm of this lever engages in a recess or notch 16 in the cap 2' and is provided with a lug 14', which is adapted to engage in a recess or notch 16', provided in the lower portion of the valve-plug B. A partition or disk 17, having the slot 17', through which the long arm of the lever extends, is loosely retained near the bottom of the piston 7 by means of the ring 18 secured therein and is permitted to turn with the lever 14 as the cap 2' is being screwed into or out of the casing 1. The purpose of this partition is to move the lever 14 on its fulcrum as the piston 7 ascends, and thus cause the lug 14' to recede from the recess 16 and unlock the plug B when the pis-

ton is shot, as shown in Fig. 5. An expansion-spring 19, which is incased within the recess 20 and cap 21, is adapted to bear against the short arm of the lever 14 and normally retain the lever in locked position when the piston is down, as shown in Fig. 4. The expansion-spring 6' answers the same purpose as the spring 6 in Figs. 1 and 2. It will thus be seen that the device shown in Figs. 1 and 2 can readily be equipped with my improved lock by substituting the cap 2' and the slotted disk 5" (shown in Figs. 4 and 5) for the cap 2 and perforated disk 5 and securing the partition or disk 17 in the piston 7.

One of the most important advantages of my improved angle-cock and safety-valve is in reducing the labor of brakemen in switching cars and giving them, through the handle of the angle-cock, practically the same control of a detached car or cars as the engineer has of his train by the use of the engineer's valve. Suppose a car has been detached from a moving train and is running in a westerly direction, the angle-cock on the front or west end of the car being closed and that on the east end open, with the valve therein shot, as shown in Fig. 2, caused by disconnecting the hose-couplings between the train and the detached car. When the valve on the east end of the car is shot and the handle of the angle-cock open, a gradual leakage takes place between the piston 7 and the casing of the chamber 4 and out through the passage-way 12 to the atmosphere, thereby causing the brakes to be gradually applied and the car caused to stop slowly. If the brakeman finds that the car is not going far enough, he can turn the handle C from position α' to what is termed "on-lap" position, (shown in Fig. 6 by dotted line γ'), thereby stopping the exhaust through the port 12. The pressure in the chamber 1' is maintained equal to that in the train-line through the passage-way 10, which is still in communication with the train-line, thus preventing the release of the valve and stopping of the car. If desired to run the car still farther after the handle has been placed in this lap position, the brakeman by giving a slight pull on the wire connected with the release-valve of the auxiliary reservoir can release the brakes from the wheels and allow the car to proceed. When the car has traveled the desired distance, the brakeman can either cause the same to stop gradually by throwing the handle to the position α' , Fig. 6, and causing a retarded exhaust through the port 12, or he can set the brakes suddenly by turning the handle from the position α' to the position γ' , Fig. 3, (thus closing the passage-way 10 and allowing the air in the chambers 1', 4, and 7' to exhaust to the atmosphere through the passage-way 11 and the valve to return to its normal open position,) and then turning the handle back to the position α' , leaving the an-

gle-cock in full-open position, as shown in Fig. 1, and causing an emergency application of the brakes by reason of the sudden reduction of pressure in the train-line. The pressure at 5 the bottom of the piston having been exhausted by turning the handle to the position y' , the valve will not be again closed by reason of the sudden exhaust through the train-line when the handle is turned to the position x' .

15 In speaking of the emergency application I do not wish it to be understood that my valve will in any way affect or prevent the emergency application of the brakes when applied from the engine, the engineer having the same 15 control of his train as he would if my valve were not on the angle-cock.

It may happen that the brakeman will neglect to unseat the valves when he couples up 20 the cars of a train that has broken in two, and it is important that the engineer be able to unseat said valves from the engine. With 25 my improved valves this may be done, as follows: The seated valve nearest the engine may be unseated by the engineer drawing off the air from the front portion of the train and from the bottom of the piston through the passage 10, allowing the valve to drop from gravity. The engineer may then unseat the other valve, if for any reason it remains seat-

30 ed, by recharging the line and driving the air through port 12 on top of the piston, forcing it down. Again, my invention will prevent 35 injuries to brakemen, as follows: Under the present system when a car is to be picked up and cut into a train charged with air both angle-cocks where the train is to be separated are turned off before the hose is uncoupled, so as to retain the pressure in both sections 40 of the train while the switching is being done.

45 In recoupling the train after the car has been picked up the brakeman has to reach over the draw-bar to open the angle-cock on the opposite side after the coupling has been made, and in this way many accidents occur by the 50 brakeman having his arm or body caught and crushed between the bumpers of the two cars. With my improvement danger from this source is avoided, the operation being as follows: The angle-cocks are not touched until 55 the valves are both shot by the uncoupling of the hose, after which they are both turned to "lap" position to shut off all escape of air.

When the train is ready to be recoupled, the brakeman turns the handle of the angle-cock 55 on the rear section to "open" or x' position while the front section is approaching, the valve in said angle-cock being still closed. If the handle of the angle-cock on the approaching section is not already in "closed" or y' 60 position, he turns it to that position and permits the valve to drop before he makes his coupling. After the coupling is made the brakeman opens the angle-cock on the forward section by turning the handle to x' po-

sition, and the pressure through the port 12 65 on top of the piston in the other angle-cock opens the valve therein, thus avoiding the necessity of the brakeman reaching over the draw-bar to open the same. The purpose of the brakeman so manipulating the angle-cock 70 on the engineer's side would only be to save air, since the engineer could, if necessary, release the valve on his side by drawing off the air from the line in the manner above indicated.

I do not restrict my invention to the form, dimension, or location of parts shown, since many of the parts may obviously be changed in form or location without substantially varying the mode of operation or principles of my 80 invention.

Having thus described my invention, what I claim as new, and desire to secure by Letters Patent, is—

1. An angle-cock of a fluid-pressure system, 85 a cylinder or chamber attached thereto, a hollow plug adapted to be turned by the handle of the angle-cock, said hollow plug having a piston with a hollow stem attachment thereto, all adapted and arranged in the angle-cock 90 that the fluid-pressure of the fluid system through the angle-cock can be controlled and regulated.

2. In an angle-cock for fluid-pressure systems, a hollow valve-plug adapted to be turned 95 to open and close the passage-way therein, a chamber, a cylindrical extension on said valve-plug within said chamber, a movable element in said cylindrical extension adapted when moved to close the passage-way in said 100 angle-cock, means for admitting air under pressure below said movable element, and means for exhausting the air therefrom when the plug is turned.

3. An angle-cock for fluid-pressure systems 105 having a passage-way therethrough, a hollow valve-plug having a cylindrical extension and adapted when turned to open and close the passage-way in said angle-cock, a hollow piston and connected valve-stem in the extended 110 portion of said valve-plug, and means for admitting air under pressure below and within said piston and stem for causing the same to move when the pressure above the same is reduced and close the passage-way in said angle-cock.

4. In an angle-cock for fluid-pressure systems, a hollow valve-plug having a cylindrical extension thereon, means for admitting air under pressure to the bottom of said plug, a 120 piston and valve member in said plug adapted to close the passage-way in said angle-cock when pressure is applied to the under side of said piston, a passage-way provided to release the air from the bottom of said plug when turned in closed position, and a port leading from the passage-way in said angle-cock to the interior of said plug above said piston.

5. An angle-cock for fluid-pressure brake systems having a normally open conduit therein, a chamber, a hollow cylindrical valve-plug extended within said chamber and adapted to 5 be turned and close said conduit, a piston and valve-stem in said plug adapted to be moved into the line of said conduit and close the same, a passage-way for admitting fluid to the bottom of said chamber and plug when said 10 plug is in open position, and the passage-way for permitting fluid to exhaust from said chamber and plug when said plug is in closed position.

6. A stop-cock for fluid-pressure systems 15 having a normally open conduit therein, a chamber, a hollow cylindrical valve-plug extended within said chamber and adapted to open and close said conduit, a piston and connected valve-stem in said valve-plug and adapted to normally 20 remain out of the line of said conduit, means for equalizing the fluid-pressure below said piston with that in the conduit when said valve-plug is in open position, means for exhausting the pressure from below said piston 25 when said plug is in closed position, and a passage-way affording communication between the said plug above said piston and said conduit when the plug is in substantially open position.

30 7. An angle-cock for fluid-pressure systems having a conduit, an extended hollow valve-plug adapted to open and close said conduit, a hollow piston and connected valve-stem in the extended portion of said plug adapted 35 when pressure is applied from one side to seat in the conduit and close the same, ingress and egress passages for fluid to pass to and from the extended portion of said valve-plug below said piston and stem when the said plug 40 is in open and closed positions, respectively, and means provided for permitting fluid to pass to and from the extended portion of said plug above said piston for the purpose described when said valve-stem is seated and said 45 plug is in open position.

8. An angle-cock for fluid-pressure systems having a conduit, a chamber, a hollow valve-plug extended within said chamber, a piston and connected valve-stem in said valve-plug 50 and adapted to seat in and close said conduit, communication between said chamber and plug below said piston, the ingress-passage 10 and egress-passage 11 to and from said chamber when said plug is in open and closed positions, respectively, and the passage-way 12 leading to the top of said piston.

9. An angle-cock for fluid-pressure systems having a conduit, a hollow valve-plug adapted to open and close said conduit, a movable 60 element adapted when pressure is applied on one side thereof to seat in and close said conduit, passage-ways leading to the bottom and top of said element and so arranged as to adapt them to both be open, or one be open

and the other closed, or both be closed according to the degree of movement of said plug with respect to said conduit. 65

10. An angle-cock for fluid-pressure systems having a conduit, a valve-plug adapted to open and close said conduit, a movable element adapted when pressure is applied to one side thereof to move in the line of and close said conduit, passage-ways leading to the bottom and top of said element and so arranged as to adapt them to both be open to said conduit, or one be open and the other closed, or both be closed according to the degree of movement of the said valve-plug, and an egress passage-way from the bottom of said element when both of said passage-ways are closed. 70 75 80

11. In an air-brake system, an angle-cock having a hollow plug turnable by the handle of the angle-cock, the lower portion of said hollow plug forming a cylinder or chamber 85 and holding therein a piston with stem attachment, said chamber so in communication and connection with the air-line through the angle-cock that the engineer can operate the piston from the engine by air-pressure to open the angle-cock after the piston has closed the angle-cock. 90 95

12. The combination, in an angle-cock, of the hollow angle-cock plug B carrying the chamber 4 in the chamber 1', both of said chambers being in communication with the passage-way of the angle-cock, and the piston 7 in said chamber 1 adapted with stem 8 to open and close said passage-way by fluid-pressure, substantially as described. 100

13. In a fluid-pressure brake system, an angle-cock having a turnable plug with a chamber and movable element therein adapted to close the main passage-way of the angle-cock by fluid-pressure, a pivoted arm in contact 105 with said movable element so adjusted as to lock said plug from turning when the movable element does not close the air-passage, and to unlock the plug by the action of the movable element in closing the air-passage. 110

14. The combination, with an angle-cock for fluid-pressure systems having a conduit, a valve-plug adapted to turn and open and close said conduit, and a movable element adapted to be moved by pressure into the line of said conduit, of a lever adapted to normally engage said valve-plug and prevent it from being turned, the said lever having engagement with said movable member whereby as the said member is moved from its normal position the said lever is caused to release said plug and permit its being turned. 115

15. The combination, with an angle-cock for fluid-pressure systems having a conduit, a valve-plug for opening and closing said conduit, and a movable valve adapted to seat in and close said conduit when pressure is applied to one side thereof, of a movable mem- 120 125

ber having engagement with said valve-plug to prevent its being turned when said conduit is open, and adapted to be moved out of engagement with the said plug when said valve 5 is driven to its seat in the conduit.

16. The combination, with an angle-cock for fluid-pressure systems having a conduit, a valve-plug for opening and closing said conduit, and a movable element adapted to seat 10 in and close said conduit when pressure from said conduit is applied to one side thereof, of a member having a long and a short arm fulcrumed adjacent to the lower portion of said plug, the said short arm adapted to normally 15 engage said plug and prevent its being turned and the long arm to engage said movable element and be moved thereby in its seating movement causing the said short arm to re-cede from said plug and permit the turning 20 thereof.

17. The combination, with an angle-cock for the purpose described having a conduit and a hollow valve-plug for opening and closing said conduit, of a movable element in said

25 plug, a lever fulcrumed below said valve-plug, the said lever having one arm in engagement with said movable element and adapted to be moved thereby and its other arm normally engaged with said plug to prevent the same from turning, and means provided for moving 30 said element and causing said lever to be disengaged from said plug.

18. The combination, in an angle-cock, of the hollow plug B carrying the chamber 4 in the chamber 1, both of said chambers being 35 in communication with the passage-way of the angle-cock, the piston 7 in said chamber 4 adapted with stem 8 to open and close said passage-way by fluid-pressure, and the lock 14 adapted to lock and unlock the turning of 40 said plug B, substantially as described.

In testimony whereof I have signed my name to this specification in the presence of two subscribing witnesses.

FRANK B. MORRISON.
